CLAIM

The ornamental design for a skin treatment tip as shown and described herein.

DESCRIPTION

FIG. 1 is a front perspective view of a skin treatment tip showing a first embodiment of the design.

FIG. 2 is a rear perspective view of the skin treatment tip of FIG. 1.

FIG. 3 is a front view of the skin treatment tip of FIG. 1.

FIG. 4 is a rear view of the skin treatment tip of FIG. 1.

FIG. 5 is a left side view of the skin treatment tip of FIG. 1.

FIG. 6 is a right side view of the skin treatment tip of FIG. 1.

FIG. 7 is a top view of the skin treatment tip of FIG. 1.

FIG. 8 is a bottom view of the skin treatment tip of FIG. 1.

FIG. 9 is a front perspective view of a skin treatment tip showing a second embodiment of the design.

FIG. 10 is a rear perspective view of the skin treatment tip of FIG. 9.

FIG. 11 is a front view of the skin treatment tip of FIG. 9.

FIG. 12 is a rear view of the skin treatment tip of FIG. 9.

FIG. 13 is a left side view of the skin treatment tip of FIG. 9.

FIG. 14 is a right side view of the skin treatment tip of FIG. 9.

FIG. 15 is a top view of the skin treatment tip of FIG. 9; and,

FIG. 16 is a bottom view of the skin treatment tip of FIG. 9.

The broken lines in FIGS. 9-16 illustrate portions of the skin treatment tip that form no part of the claimed design.
